UNITED STATES PATENT OFFICE.

FRANK A. GAUGER, OF MILWAUKEE, WISCONSIN, ASSIGNOR TO TIME-O-STAT CORPORATION, OF MILWAUKEE, WISCONSIN, A CORPORATION OF WISCONSIN.

THERMOSTATIC CONTROL FOR OVENS.

Application filed December 22, 1924. Serial No. 757,445.

This invention relates to thermostatic control for the ovens of gas ranges.

Thermostatic controls for gas ovens have been provided, but in devices thus far produced it has been necessary to employ additional piping and fittings in order to connect the gas supply with the thermostatic element. This has resulted in an expensive construction both for material and for the 10 labor involved in assembling it.

This invention is designed to overcome these defects, and objects of the invention are, therefore, to provide a thermostatic control for gas ovens which may be attached to 15 the usual burner supply header, which extends horizontally across the front of the range, and to so construct this control unit that it is applicable to and easily positioned within the conventional type of gas oven 20 with a minimum of change and without requiring any additional fittings or piping whatsoever. More specifically, this invention has for its object to provide a thermostatic control unit which may be attached 25 directly to the end of the usual burner supply header, and which will project diagonally into the oven preferably between the lining and the side wall thereof.

An embodiment of the invention is shown 30 in the accompanying drawings, in which:—

Figure 1 is a partially developed section through the device and oven and through a portion of the oven burner manifold.

Figure 2 is a transverse sectional view 35 through the oven showing the position of the device with reference to the main body of the oven.

Figure 3 is a fragmentary sectional view 40 partly broken away, on the line 3—3 of Figure 1.

Referring to the drawings, it will be seen that the usual burner supply header 1 has been shown which normally supplies the burners for the top portion of the range one 45 of whose manifolds is indicated at 2. This header also normally supplies the burner 3^a for the oven, such burner having its manifold indicated at 3. In the usual type of range, the oven is positioned adjacent the 50 end of the burner supply header 1, as shown in Figure 1, and this oven usually consists of an outer wall 4 which may be either single or double and is usually provided with an inner lining 5 spaced from such outer 55 wall and terminating at a material distance

below the top of the oven, as shown in Figure 2. A marginal front edge strip 6 extends from the front edge of the outer wall 4 to the front edge of the lining 5 and provides the casing or frame for the door 7 of 60 the oven.

It is proposed in this invention to attach to the end of the burner supply header 1 a thermostatic unit which projects upwardly and diagonally into the oven, as shown in 65 Figure 2. This thermostatic unit also includes the nozzle 8 for the oven burner manifold 3. As shown in Figure 1 it preferably consists of a body portion 9 which is screwed directly upon the end of the header 70 1 if the header is of such length as to correctly position the unit. If, however, the header extends slightly beyond the correct position for the unit, the extreme end is sawed off and is threaded and the unit is 75 screwed upon such end. This main body portion is provided with a main supply duct 10 and with a valve seat 11 provided with a plurality of apertures 12 arranged in a ring. From these apertures the gas passes 80 through a duct 13 to the nozzle 8. The flow of gas through the apertures 12 is controlled by means of an annular valve 14 which is provided with a groove in its annular face, as shown, and which is provided with a plurality of apertures 15 communicating with its central portion, as shown clearly in Figures 1 and 3. This valve is yieldingly held 85 in place by means of a spring 16. The valve is adapted to be unseated by means of a rod 90 17 carried in a tube 19 and rigidly and detachably connected with said tube at its outer end by means of the cap 19. This rod 17 is provided with a shoulder which contacts with the valve 14 and under pre-determined conditions overcomes the actions 95 of the spring 16 and unseats the valve. In fact this apparatus may be of any desired type such for instance as that disclosed in my Patent Number 1,569,474, issued to me 100 January 12, 1926, for oven regulator. The adjustment of the device is secured by means of a hand wheel 20 which is screwed fast to a shaft 21 which is preferably provided with a rectangular aperture adapted to receive the rectangular end 22 of the rod 17, as shown in Figure 1.

In order to position the thermostatic element within the oven, a small hole 23 is bored through the marginal front edge strip 110

6 adjacent its lower portion, and the element projects upwardly and diagonally into the oven through this aperture 23, as shown clearly in Figures 1 and 2.

5 Due to this construction all additional piping and all additional fittings are avoided and the thermostatic unit is screwed directly to the usual burner supply header 1 projects directly into the oven without any 10 intermediate mechanism or piping.

It is to be understood that a valve such as shown at 24, for instance, may be interposed in the gas supply line intermediate the thermostatically controlled valve 14 and 15 the manifold 2 for controlling the flow of gas to the oven burner. The oven pilot burner duct or pipe is shown at 25 extending from the thermostatic valve casing through the front wall of the burner compartment and terminating in igniting relation to the oven burner as shown at 25^a. This pilot burner pipe communicates with the interior of the thermostatic valve casing on the supply side of the valve 14 so as to 25 be supplied with gas all the time valve 24 is open, regardless of the position of the valve 14.

It is to be particularly noted that due to the diagonal arrangement of the thermostatic element in the oven wall that an average temperature of the entire oven is secured. This is not the case with thermostatic elements positioned transversely of the oven no matter where they are located. 35 If they extend across the oven parallel to the door of the oven, they will be in a zone of heat materially different from that existing in other portions of the oven. If, however, as in this invention, the thermostatic 40 element is positioned diagonally of the oven and extending from the front to the rear, it is clear that it passes through several zones of heat and registers accurately the average temperature of the oven.

45 It is to be noted particularly that this thermostatic element is not positioned adjacent the upper portion of the oven door where it would be subjected to very great fluctuations in temperature in opening and 50 closing the door even for brief intervals and consequently could not, because of these conditions, register the average temperature of the oven.

It is to be noted further that due to the 55 peculiar diagonal arrangement of the thermostatic element that it is possible to attach the element directly to the actual header directly in front of the oven, and it is not necessary to attach it to any of the 60 side supply pipes for the oven.

Further, by means of the diagonal arrangement disclosed in this invention, it is possible to employ rigid expandible members for the thermostatic element, as these members project directly from the thermostatic

element diagonally into the oven. Consequently, even with rigid expandible thermostatic elements, the average temperature of the oven may be registered and also the thermostatic element may be directly attached to the header in front of the oven. 70

It will thus be seen that the thermostatic control for gas ovens has been very greatly improved and simplified, that is less expensive although an equally effective construction has been provided. 75

It will also be seen that this thermostatic control may be most readily applied to existing types of gas ranges with a minimum of change and with a minimum of expense. 80

Although the invention has been described in considerable detail, it is to be understood that the invention may be variously embodied and is, therefore, to be limited only as claimed. 85

I claim:

1. In a gas range, the combination of a burner supply header, an oven located adjacent said header, a burner for said oven, and a thermostatic control unit for the oven 90 burner, said unit being directly attached to said header and extending diagonally into said oven and positioned closely adjacent a vertical wall thereof.

2. In a gas range, the combination of a 95 burner supply header, an oven located adjacent said header, a burner for said oven, a thermostatic control unit for said burner, said unit being attached to said header and extending diagonally into said oven, said 100 oven having walls with linings spaced therefrom and said thermostatic element extending between a lining and the corresponding wall.

3. In a gas range the combination of a 105 burner supply header, an oven located adjacent one end of said header, a burner for said oven, said oven having a side wall and a lining spaced therefrom and having a marginal edge strip adjacent the door and 110 extending from said side wall across the front edge of said lining, and a thermostatic unit for said burner, said unit being attached directly to said header and extending upwardly and diagonally into said oven between said lining and said wall and through said marginal edge strip. 115

4. In a gas range the combination of a burner supply header extending horizontally across the front of said range, an oven 120 located adjacent one end of said header and having a side wall and a lining and having a marginal strip extending across the front edge of said liner and said side wall, a burner for said oven, and a unitary thermostatic device screwed directly upon the end of said header and controlling said burner, said thermostatic device having an elongated tubular device extending through the lower 125 edge of said marginal strip and extending 130

diagonally into said oven between said lining and said side wall.

5. In a gas range the combination of a burner supply header, an oven located adjacent said header, a burner for said oven, and a thermostatic control unit for said oven burner, said unit being directly attached to said header and extending diagonally into the oven and positioned closely adjacent a vertical wall, said element including rigid thermostatic members extending directly from the portion of the unit attached to said header and projecting along a diagonal line into the oven.

15. 6. The combination with a gas stove having the usual cooking top, oven adjacent thereto, supply header extending along in front of the cooking top and terminating near the oven, and burner manifolds leading from said header; of a thermostatic control device mounted on the end of said header adjacent the oven and comprising a valve casing, a valve therein, a connection between the casing and the oven burner manifold, and an elongated thermostat extending co-axially with said valve upwardly at an angle into said oven adjacent one of the vertical walls thereof, said thermostat operating to actuate and control said valve.

30. 7. The combination with a gas stove having the usual cooking top, oven adjacent thereto, supply header extending along in front of the cooking top and terminating near the oven, and burner manifolds leading from said header; of a thermostatic control device mounted on the end of said header adjacent the oven and comprising a valve casing, a valve therein, a connection between the casing and the oven burner manifold, an elongated rod for actuating said valve, said rod extending co-axially with said valve upwardly at an angle into said oven adjacent one of the vertical walls thereof, and an expandable element subject to the heat of the oven for actuating said rod.

45. 8. In a device of the character described, the combination with a stove having an oven, a supply header, an oven burner and a manifold leading to said burner from a point laterally adjacent said header, of a ported valve casing in communication with said header and supported therefrom in a position offset from said manifold along the header, a valve within the casing, a return connection affording direct communication between the casing and the manifold in the normal operation of the latter, a thermostat having a heat sensitive portion within the oven and extending substantially co-axially with said valve upwardly and rearwardly therefrom and serving to control and regulate the same.

60. 9. In a device of the character described, the combination with a cabinet gas range including a plurality of burners, a supply

header extending across said range in front of said burners, an oven above one of said burners and provided with a door and a side wall adjacent the door, and a manifold leading to said last mentioned burner from a point adjacent said header, of a valve casing supported from said header and having an inlet port in communication therewith and having an outlet port in communication with said manifold, a valve within said casing, a thermostat extending at an upwardly inclined angle from said casing and entering said oven between said door and said wall, and serving to regulate and control said valve.

70. 10. The combination with the supply header of a gas stove and a nearby oven having a single aperture in its frame, of a valved casing supported from the header, and a thermostat for operating said valve, said thermostat extending upwardly and rearwardly from said casing co-axially of said valve and through said aperture into the interior of said oven adjacent one of the vertical walls thereof.

75. 11. In a device of the character described, the combination with a gas stove having a supply header, an oven provided with a door frame having an aperture therein, and a manifold leading beneath said oven; of a valve casing in communication with said header and said manifold and supported from said header in a position directly in front of the apertured portion of said frame, a valve within said casing, and an elongated tubular thermostat for operating and controlling said valve, said thermostat being supported by said casing and extending upwardly and rearwardly therefrom through said aperture into the interior of said oven.

80. 12. The combination with a gas stove having an oven provided with an apertured door frame, an oven manifold and a supply header extending across the front of said stove and terminating adjacent the front of said oven and therebeneath, of a manually operable gas cock applied to the end of said header, an automatic gas connected with said first mentioned gas cock and provided with a valve controlling communication between said first mentioned gas cock and said manifold, a thermostat within said oven for operating said valve, said thermostat extending angularly downwardly and forwardly in a straight line to said automatic gas cock and supported thereby.

85. 13. The combination with a cabinet gas range, comprising a cooking top having a plurality of burners therebeneath, an oven at one side of the cooking top, a supply header extending across the front of the cooking top, a burner beneath said oven, a manifold leading from intermediate portions of said header to the several burners aforesaid, of a valve casing applied to said

header in front of one side of said oven and communicating with the manifold leading to the oven burner aforesaid, and a thermostat for operating said valve, said thermostat being carried by said casing and extending upwardly and rearwardly therefrom substantially co-axially of said valve and into said oven.

14. In a device of the character described, the combination with an oven having an aperture therein, of a valve casing fixed with reference to said oven in a position in advance thereof and below said aperture, a valve within said casing, a heat responsive element disposed within the oven, and a rod co-axial with said valve projecting upwardly and rearwardly from said casing in a substantially straight line through said aperture, said rod engaging said heat responsive element and serving to transmit motion therefrom to said valve to control and regulate the latter.

15. The combination with a gas stove having the usual cooking top, oven adjacent thereto, supply header extending along in front of the cooking top and terminating near the oven, and burner manifolds leading from said header; of a thermostatic control device adjacent the oven and communicating with said header and comprising a valve casing, a valve therein, a spring normally urging said valve in one direction, a connection between the casing and the

oven burner manifold, an elongated rod for actuating said valve in opposition to said spring, said rod extending co-axially with said valve upwardly at an angle into said oven, adjacent one of the vertical walls thereof, and an expansible element subject to the heat of the oven for imparting the valve actuating movements to said rod.

16. In a device of the character described, the combination with a gas range including a plurality of burners, a supply header extending across said range in front of said burners, an oven above one of said burners and provided with a door and a side wall adjacent the door, and a manifold leading to said last mentioned burner from a point adjacent said header; of a valve casing supported in communication with said header and having an outlet port in communication with said manifold, a valve within said casing, a heat responsive element disposed within the oven, and a rod co-axial with said valve projecting at an angle from said casing and entering said oven between said door and said wall, said rod engaging said heat responsive element and serving to transmit motion therefrom to said valve to control and regulate the latter.

In testimony that I claim the foregoing I have hereunto set my hand at Milwaukee, in the county of Milwaukee and State of Wisconsin.

FRANK A. GAUGER.

4

header in front of one side of said oven and communicating with the manifold leading to the oven burner aforesaid, and a thermostat for operating said valve, said thermostat being carried by said casing and extending upwardly and rearwardly therefrom substantially co-axially of said valve and into said oven.

14. In a device of the character described, the combination with an oven having an aperture therein, of a valve casing fixed with reference to said oven in a position in advance thereof and below said aperture, a valve within said casing, a heat responsive element disposed within the oven, and a rod co-axial with said valve projecting upwardly and rearwardly from said casing in a substantially straight line through said aperture, said rod engaging said heat responsive element and serving to transmit motion therefrom to said valve to control and regulate the latter.

15. The combination with a gas stove having the usual cooking top, oven adjacent thereto, supply header extending along in front of the cooking top and terminating near the oven, and burner manifolds leading from said header; of a thermostatic control device adjacent the oven and communicating with said header and comprising a valve casing, a valve therein, a spring normally urging said valve in one direction, a connection between the casing and the

oven burner manifold, an elongated rod for actuating said valve in opposition to said spring, said rod extending co-axially with said valve upwardly at an angle into said oven adjacent one of the vertical walls thereof, and an expansible element subject to the heat of the oven for imparting the valve actuating movements to said rod.

16. In a device of the character described, the combination with a gas range including a plurality of burners, a supply header extending across said range in front of said burners, an oven above one of said burners and provided with a door and a side wall adjacent the door, and a manifold leading to said last mentioned burner from a point adjacent said header; of a valve casing supported in communication with said header and having an outlet port in communication with said manifold, a valve within said casing, a heat responsive element disposed within the oven, and a rod co-axial with said valve projecting at an angle from said casing and entering said oven between said door and said wall, said rod engaging said heat responsive element and serving to transmit motion therefrom to said valve to control and regulate the latter.

In testimony that I claim the foregoing I have hereunto set my hand at Milwaukee, in the county of Milwaukee and State of Wisconsin.
